UNITED STATES PATENT OFFICE.

WILLIAM F. FRECH, OF BROOKLYN, NEW YORK, ASSIGNOR TO CARY MANUFACTURING CO., OF BROOKLYN, NEW YORK, A CORPORATION OF NEW YORK.

MACHINE FOR DEFORMING WIRE IN DEFINITE LENGTHS.

Application filed November 17, 1923. Serial No. 675,255.

This invention is a machine for producing deformed wire in definite lengths, the object being to automatically manipulate wire drawn from a coil so as to straighten, 5 cut to a determined length, and deform an end portion (one or both) of the lengths of wire so as to render the same available for use as package binders.

In certain particulars, the machine of this 10 invention is of the character disclosed in Hoefer, Patent No. 729,864, wherein means are provided for feeding wire drawn from a coil through a straightening mechanism and moving such straightened wire relatively to length-gaging means and to cutting means, which means are mutually co-operable in determining the length to be cut from the continuous wire, producing a 15 multiplicity of straightened pieces of a definite length.

Machines of the Hoefer type do not operate to deform an end portion of the cut lengths of wire, nor are such machines sufficiently stable to withstand the strain of the 20 deforming operation. Accordingly, my invention includes a structure by which the wire is deformed concurrently with the operations of feeding, straightening, gaging and cutting to length a strand from a coil.

According to my invention, co-operable 25 deforming dies are provided, there being a stationary deforming die upon a head of a frame column or pedestal and a movable deforming die on a rocking arm or lever, 30 and with said deforming dies co-operates a cutter which is movable with the rocking arm or lever. Said cutter, however, does not occupy a shearing relation to a tubular member through which the wire strand is 35 fed, but, on the contrary, this cutter is in a remote relation to said tubular member, said cutter member being movable with the rocking arm or lever in a shearing relation 40 to a stationary shear plate in a spaced relation to the tubular feed member, so that the stationary deforming die occupies an operative position intermediate the tubular feed member and said stationary shear member.

For supporting the stationary deforming 45 die and the stationary shear member, I provide a bracket member which carries the two said named parts, and in order to mount said member in a stable position upon the

pedestal head, there is provided an offset bearing which is unitary with the pedestal head by being cast solidly therewith, said offset bearing affording the required solid support for the supporting bracket and presenting below the tubular feed member a shoulder upon which the bearing bracket 55 is seated and to which offset bearing the supporting member is rigidly attached.

The stationary shear member is positioned parallel to the stationary deforming die, there being an appreciable interval between 60 the proximate edges of the shear member and the deforming die. Said stationary deforming die and the stationary shear member are close to the path of feed of the wire strand, below the same, there being 65 only a sufficient interval for the wire to pass freely over said die and shear member with no appreciable opportunity for the depression of the wire strand from its normal plane of feed when operated upon by the 70 co-operable deforming dies and the co-operable cutter and shear member. Furthermore, the tubular feed member is supported within the pedestal head for the vertical face at the delivery end of said tubular member to occupy a spaced relation to the proximate face of the lower swaging die 75 so that the wire strand extends through and beyond the tubular feed member, through a space between said delivery end of said tubular member and the deforming die adjacent thereto, thence over the top face of 80 said deforming die, across the shear plate, and thence into the wire receiving member.

The movable deforming die and the movable cutter are fixedly engaged with the head, which head is in turn fixedly secured in a short arm of the rockable lever. Said die-and-cutter head is grooved to receive the deforming die and also grooved to receive the cutter, the two said parts being 85 separately attached to said head. The cutter and the movable die are parallel to each other, with a space of appreciable width intervening said die and cutter, and the die-and-cutter head is so positioned on the rockable lever that in service the movable deforming die and the movable cutter co-operate with the stationary deforming die and the stationary shear member, respectively. The wire is fed intermediate the 90

two dies and the two cutter members, and in service, the action of the rockable arm is so timed with reference to the feed of the wire that when the required length is advanced beyond the shear plate adjacent the tubular feed member, as determined by the wire-length-gaging devices, said dies act on the wire to deform it near one end and the cutter shears past the shear plate concurrently with the deforming action so as to sever the previously fed length of wire from that part of the strand, one end of which has just been subjected to the deforming action of the dies.

15 The wire at the deforming and cutting operation is fed continuously, hence the straightener head is mounted to have a limited sliding action, and the rockable lever is given a quick motion by a cam; but notwithstanding these conditions in service the feed movement of the wire at the deforming and cutting operation has a tendency to press the severed end of the wire into such frictional contact with the face 20 of the cutter that on the return of said cutter to a position away from the shear member said severed end of the wire has a tendency to follow the upward travel of the cutter; in other words, the frictional engagement 25 of the severed end with the cutter face results in a certain adhesion of one surface to the other which has a tendency to interfere to some extent with the wire feed and to slow up the productive capacity of the 30 machine. To overcome this condition, I provide a wire displacing member in the form of a spring backed plunger carried by the die-and-cutter head and positioned intermediate the movable deforming die and 35 the movable cutter, said plunger normally occupying a position with respect to the operating face of the die and the shearing edge of the cutter that at the instant said die and cutter begin their return movement 40 toward a normal position the plunger displaces the severed end of the wire from contact with the face of the cutter, whereby the wire cut end is forced downward below the shearing edge of the cutter and the feed 45 of the wire takes place without stoppage and without bending the deformed end portion of said wire.

Other features and advantages of the invention will appear from the following description taken in connection with the drawings—wherein—

Figure 1 is a side elevation of the machine.

Figure 2 is a vertical cross section illustrating the rockable lever and the deforming die mechanism in elevation.

Figure 3 is a plan of a part of the machine showing the wire-feed rolls and the rotary die head for straightening the wire.

Figure 4 is an enlarged view of parts in side elevation illustrating the pedestal head

with the integral offset bearing and the bracket for the stationary die and the shear member, and also showing the head for the movable die and the movable cutter, the rockable arm being in dotted lines.

70

Figure 5 is a vertical sectional elevation taken in the direction of the axis of the tubular wire feed member, illustrating the deforming means and the cutting means in relation to said tubular member and certain of the other parts of said Hoefer machine.

Figure 13 is a section on the line 13—13 of Figure 12 illustrating a trip controlled detent.

100

The operating mechanism is carried by and within a hollow pedestal A provided with a number of bearings (not shown) for supporting a drive shaft B, a countershaft C, and vertically-positioned roll shafts d d which carry the feed rolls D D. The drive shaft B is equipped with fast pulleys b b and a loose pulley b', and from one fast pulley b runs a belt e which drives a pulley e' which is fast with a horizontally positioned rotary and sliding head E. As is usual, said head is equipped with dies (not shown) for acting upon the wire strand X in the usual manner, whereby the rotary motion of the head and the action of the dies operate to straighten the wire strand as it is drawn from a coil. This head E is journaled in and fitted loosely within bearings e² of a yoke e³ which is rigid with the machine frame, said sliding motion of the rotary head functioning as a compensating means for the back thrust on the wire as it contacts for a brief interval of time

105

with the face of the movable cutter as the latter severs the wire and recedes from the cut end of said wire during the continuous feed thereof by the action of the rolls D D. The countershaft C and roll shafts d d

110

115

120

125

130

135

are driven by the motion of the drive shaft, and on the countershaft is a balance wheel F and a plurality of clutch members f f', one of which is loose on the shaft C, and the other is fast therewith, with provision such as clutch pin f² for automatically connecting the two clutch members f f' when the desired length of wire shall have been fed so that a tripping or gaging mechanism will set in motion the means for actuating the rockable lever G whereby the operations of deforming and cutting the wire are effected automatically and in timed relation to the feed of said wire. The loose clutch member f' controls a cam g with which contacts a track roll g' mounted on the lower part of lever G, the latter being vertically positioned alongside the pedestal A and being fulcrumed by a spindle g² on the pedestal head A'. As shown in Figures 1, 2, 4 and 5, the pedestal head is separate from the pedestal, the said head A' being cast in a single piece of heavy construction to resist the strains, and being provided with an offset base flange a to the end that the head may be seated solidly upon the top end of the pedestal and be clamped immovably thereon by the binding screws a', whereby the head will not become loose on the pedestal under the jar and vibration of the working parts. The rockable lever is reinforced and stiffened by the provision of ribs or webs h' so that it is sufficiently strong to withstand the effects of the deforming dies and the cutting means without resulting in fractures of said lever. As shown, the lever has a short upper arm G' in elevated relation to the tubular feed member H which is fixedly mounted in the head A', see Figure 5, and to this lever is connected a spring h² acting to throw the lever to a normal position and to retain the track roll in contact with the cam g, see Figure 2.

I is a wire receiver shown as a horizontal bar or rail supported in a fixed position by the machine frame and by a supporting leg i. This rail is provided in its underside with a wire receiving channel i², see Figure 2, in the line of feed of the wire, so that the wire advanced by the feed rolls D D and straightened by the rotary head will lie within the channel of the rail at the time the deforming dies and the cutting means act upon said wire. The channel is closed normally by a closure member I', see Figures 1 and 2 in the form of a flat horizontal plate fitting snugly against the undersurface of the rail I, suitable means being provided for the automatic operation of the closure member I' in timed relation to the deforming and cutting operations.

As shown, a horizontal rock shaft I² is journaled in appropriate fixed supports i³, said shaft carrying a series of fingers j pro-

vided with notches in which are received 65 studs j' which are fast with the closure member, and co-operating with this rock shaft is a spring I⁶, see dotted lines in Figure 2, acting to turn the shaft in a direction for the fingers j to move the closure 70 member I' to a position across the channel. The rockshaft I² is provided with a rocker arm I³ which is in the path of a stud I⁴ provided on the rockable lever G, said stud acting on the arm I³ to turn the rock shaft and 75 shift the closure member I' after the deforming dies and the cutter act upon the wire length, whereby the cut and deformed wire lengths are permitted to drop by gravity out 80 of the channeled rail I and to be received 85 within the rack formed by the yoke-shaped members I⁵, see Figure 1 and dotted lines in Figure 2.

Within the channel of the rail I is positioned a trip member J in the form of a 85 rod or wire, one end portion of which is made fast with a trip slide J'. To this trip slide is attached a rod or wire K extending adjacent to the channeled rail I, the other end of which is attached to a bell crank 90 lever K', pivoted on the machine frame and operatively connected to a detent k which slides in a guideway k' and is provided with a cam face K⁵ cooperable with a head f⁴ 95 of a spring actuated clutch pin f³ by which the loose and fast clutch members are coupled at or about the time a section of wire of the desired length is fed by the rolls into the channeled rail I, whereby the contact 100 of the fed wire with the trip wire J imparts movement to the slide J' and thus the wire or rod K and the lever K' are actuated to throw the clutch members into service for the loose cam g to be made fast with shaft C and thereby the lever G is operated to 105 deform and cut the wire, whereupon the straightened and cut length of wire, deformed at one end, is dropped into the rack.

The pedestal head A' is provided with an opening l for the reception of the tubular feed member H, one end of said opening extending through the vertical face of said head, and this tubular member H is positioned partly within said opening and fixedly secured by appropriate means to said head. As shown in Figure 5, one end of the tubular member H protrudes for a suitable distance outside the head, whereas the other end of said member terminates within the opening l, said end being an appreciable distance from the vertical face of the head. As usual, the protruding end of the tubular member is tapering toward the feed rolls D D.

Said pedestal head is provided with a 125 bearing L for supporting the bracket member M solidly and immovably in the required relation to the tubular member H, said bear-

ing being preferably cast with the head and being offset from the vertical face thereof so as to present a shoulder l' below the opening l for the tubular feed member H , see Figures 1, 2 and 5.

- The bracket member shown in Figures 1, 2 and 5 and in detail in Figures 7 and 8, is formed in a single piece with lugs m depending from the body portion of said bracket member. Said bracket member is assembled for contact with the vertical face of the head A' below the opening l , said member resting, or being seated, upon the shoulder l' of the bearing L and the lugs m contacting with the vertical face of the bearing, whereby the bracket member is secured in fixed position as by screws m' passing through apertures in the lugs m and engaging holes tapped in the bearing. The bracket member is recessed in its respective faces, one of said recesses accommodating the deforming die O and the other recess receiving the shear member Q . Said die is seated firmly on the bracket member and secured fixedly thereto by screws o . The shear member Q is seated solidly in that recess which is provided in the face of the bracket member remote to the opening l in head A' , and the shear member is secured fixedly in position by screws q . The deforming die O and shear member Q are composed of pieces of hardened metal, such as steel, and they are mounted in immovable relation to each other upon the bracket member, M , with a solid wall m^2 of said bracket member, intermediate said die and shear member, see Figures 2, 5, 7 and 8. The die O is positioned on the bracket member for the top face of the die to project slightly above the corresponding face of the intervening wall m^2 , whereas the top face of the shear member is flush with said top face of the wall m^2 , so that the exposed top face of the shear member is in a plane slightly below the active face of the die. As shown in Figure 5, the active top face of the lower stationary die O is as close as it is possible to place it to the path of the wire X , but said die extends across the hole l in the head A' in a manner to partly close said hole where it opens through the vertical face of the head A' , the die O being separated from the adjacent end of the tubular member by a space of appreciable width, see Figure 5. The bracket M , deforming die O and shear member Q are assembled and positioned relatively to the bearing L , pedestal head A' and tubular member H for said die O to intervene the shear member Q and the tubular member H , so that there is a very substantial interval separating the shear member Q from the tubular member H , see Figure 5.

R is the die-and-cutter head for the movable deforming die P and the cutter S , see

Figures 4, 5, 9 and 10, said head being attached to the short arm of rockable lever G . The head R is provided with a shank r which is fitted in a recess r' of the short arm G' of lever G and is held fixedly therein by a set screw r^2 , one or more. The deforming die P is composed of a flat plate of hardened metal, and is seated in a recess provided in one side of the head R , in which recess said die is securely retained by appropriate means, such as the screws p . The cutter S is likewise composed of a piece of hardened metal with a lower beveled face s to produce a shearing edge, see Figure 10, and said cutter occupies a recess in the opposite face of the head R from that recess which accommodates the die P , the cutter being fixedly attached to the head as by screws s' . The die P and cutter S are positioned on the opposite faces of the head R with a wall r^3 of said head intervening the die and the cutter, and these parts are so related that the under face of the die P is in a plane below the corresponding face of the wall r^3 of the head R , and, furthermore, the cutting edge s of the cutter S extends below the under faces of the head R and die P , see Figure 10.

T is a plunger carried by the head R and positioned adjacent the cutter S and close to the cutting edge thereof. This plunger plays loosely in a slot t provided in the wall r^3 of the head R , and it is normally forced in one direction by a spring T' encased within the slot t , see Figure 10. The outward movement of the plunger under the pressure of the spring is arrested by suitable stop devices, indicated in Figure 10 as a short lug t' . The plunger T is intermediate the cutter and the die, and the lower active face of said plunger is below corresponding face of the die, the plunger being impelled by the spring to slide into contact with the face of the cutter S against which the cut end of the wire, advanced by the feed rolls, is adapted to contact so that the plunger displaces said cut end of the wire from such contact with the cutter subsequent to the cutting operation and upon the receding movement of the head R , die P and cutter S relatively to the wire and the other die O and shear member Q . The rockable lever swings in an arcuate path relatively to the vertical face of the pedestal head H for the die P and cutter S to move toward and from the die O and shear member Q , respectively, but as the wire to be treated is small in diameter, the stroke of the lever is a comparatively short one. The die P and cutter S are so mounted by the head R on the short lever arm that the die P coacts with the die O and the edge s of cutter S shears past the face of the shear member Q , see Figure 5, the deformation being produced on the wire at a point between the cutting mechanism and the open-

ing l of the pedestal head within which the tubular member H is positioned.

The operation will be apparent from the foregoing description taken in connection with the drawings, but may be summarized as follows:—With the loose cam g idle owing to the free or unconnected condition of the clutch and with the die P and cutter S away from the die O and shear plate owing to the action of spring h^2 on lever G , the wire is straightened by the rotary motion of head L and is advanced through tubular member H by the feed rolls D D . The wire is moved into the channel of the rail I until the advancing end of the wire contacts with the trip wire J , the length and position of which determine or gage the wire section to be deformed and cut. The movement of the wire to be cut displaces the trip wire and slide, pulls on connection K and lever K' to lift the detent k and actuate the clutch members in a manner to make the cam g fast with the shaft C at the desired period in the cycle of operations, whereupon the cam imparts rocking motion to the lever G and thereupon the die P and cutter S are moved into co-operative relation to the die O and shear member Q , respectively. The dies O P deform the wire X by swaging it at x , and the cutter severs the wire at x' (Figure 11) adjacent the deformation so as to leave a short length x^2 intermediate the cut end and the deformation. The wire is deformed by dies O P acting on the wire intermediate the co-acting cutter and shear member and the vertical face of head A' and adjacent end of tubular member H .

Following the swaging and cutting action on the wire, lever G is acted on by the spring to move the die P and cutter S away from die O and shear member Q , respectively, but prior to this receding movement, the closure plate I' is operated to open the channel i for dropping the wire and the trip devices actuate the clutch for making free the cam, as usual. During the cutting and swaging operation, the feed rolls continue their action on the wire so that the latter exerts a back thrust which slides the rotary head L a limited distance in its bearings, and owing to the continued feed of the wire the cut end is pressed frictionally against the face or edge of the cutter S , but at the beginning of the receding movement of cutter S and die P away from shear member Q and die O , the plunger T is pressed against the wire by spring T' so as to displace said wire from such frictional contact with the cutter and preclude said cut end from following the cutter in the receding travel thereof, it being apparent that the plunger T is pressed into the slot t when the dies O P act to deform the wire and cutter S coacts with member Q to shear the wire, the spring T' being compressed by such movement of plunger T and

the recoil of said spring tending to force the plunger forcibly against the wire upon the opening motion of the dies.

Having thus fully described the invention, what I claim as new and desire to secure by Letters Patent is:

1. In a machine of the class described, a frame member provided with an offstanding lug, a bracket member fixedly attached to said lug, a tubular member for the passage of a wire, a deforming die and a shear member in fixed relation to each other and carried by said bracket member in a plane below the path of feed of a wire, a moving part, a deforming die and a cutter carried by the moving part in co-operable relation respectively to the first named deforming die and the shear member, and a spring actuated plunger supported by the moving part and positioned intermediate the die and the cutter of said moving part for displacing the severed end of the wire relatively to said cutter.

2. In a machine of the class described, a frame member provided with a lug in off-standing relation to a face of said frame member, a bracket member seated upon said lug and occupying a fixed relation to the frame member, a tubular member for the passage of a wire, a deforming die carried by the bracket member, a shear member also carried by the bracket member, said shear member being spaced with respect to the deforming die, a moving part, a deforming die movable with said moving part and co-operable with the first named deforming die, a cutter carried by the moving part for co-operation with the shear member, and a spring actuated plunger positioned intermediate the second die and the second cutter for displacing the wire severed by the action of the cutter and the shear member.

3. In a machine of the class described, a tubular member for the passage of a wire, a moving part, a bracket member in fixed relation to the tubular member, a deforming die and a shear member fixedly supported by said bracket member, said deforming die and the shear member being separated one from the other by an intervening part of said bracket member, a second deforming die carried by the moving part, a cutter carried by the moving part, said second die, and the cutter being in co-operable relation to the first named die and the shear member respectively, and a spring actuated stripper positioned between the second die and the second cutter for displacing the cut end of the wire relatively to the moving part.

4. In a machine of the class described, a frame member provided with an offset bearing on the vertical face thereof, a tubular member, a moving part, a bracket member supported by the offset bearing in fixed relation to the tubular member, a deform-

ing die and shear member on said bracket member, a second deforming die movable with the moving part into co-operative relation to the first named deforming die, a cutter movable with the moving part into shearing relation to the shear member, and a spring pressed plunger movably positioned intermediate the second die and the cutter.

5. In a machine of the class described, 10 wire feeding means including a tubular member, coacting deforming dies, coacting shear members including a movable shear member, and a wire displacing plunger movable with said movable shear member to 15 preclude the cut end of a wire from following the movable shear member as the latter recedes from the companion shear member.

6. In a machine of the class described, 20 wire feeding means including a tubular member, coacting deforming dies movable relatively one to the other, coacting shear members one being movable with respect to the other, and a wire-displacing plunger co- 25 operable with one of the shear members for dislodging the cut end of a wire advanced by the feed means from frictional contact with the movable shear member.

7. In a machine of the class described, 30 wire feeding means including a tubular member, coacting deforming dies movable relatively one to the other, coacting shear members one being movable with respect to the other, and a spring-actuated displacing 35 plunger movable with the movable shear member and positioned for contact with a wire upon the separating movement of the movable shear and the movable die with

respect to the fixed shear member and the fixed die, said spring actuated plunger being 40 yieldable to the movement of the parts in the deforming and cutting operations and acting automatically to dislodge the cut end of a wire from frictional contact with the movable shear member. 45

8. In a machine of the class described, wire feeding means including a tubular member, a support, a stationary deforming die and a stationary shear member carried by said support, a moving part, a head fixed 50 to said moving part, a movable deforming die and a cutter carried by said head, and a wire displacing member carried by said head and acting on the separating movement of the parts to dislodge the cut end 55 of a wire from frictional contact with the movable cutter.

9. In a machine of the class described, wire feeding means including a tubular member, a support, a stationary deforming 60 die and a stationary shear member, carried by said support, a moving part, a head fixed to said moving part, a movable deforming die and a cutter carried by the head, and a wire displacing plunger carried by 65 said head intermediate the movable deforming die and the cutter, said wire displacing plunger being yieldably positioned relatively to the cutter and acting on the separating movement of the parts to dislodge the cut 70 end of a wire from frictional contact with said movable cutter.

In testimony whereof I have hereto signed my name this 13th day of November, 1923.

WILLIAM F. FRECH.
